ABSTRACT

A tool comprising: an elongated horizontal handle; and a vertical plate secured to one end of the handle, the handle being joined to the plate at an acute angle.

5 Claims, 4 Drawing Figures

Patented Feb. 5, 1974

FIG. 4

FIG. 3

TOOL FOR INSTALLING DISC BRAKES

SUMMARY OF THE INVENTION

My invention is directed toward a hand tool which can be used in rebuilding disc brakes by compressing the wheel cylinder far enough to set the brake pads and caliper back on the rotor whereby room is immediately made available for necessary manual adjustments.

My tool comprises an elongated horizontal handle secured at one end to a surface of a vertical plate, the handle joining or intersecting the plate at an acute angle. In use the plate is inserted into the opening between the pads and the operator pulls the handle whereby the tool permits the operator to have easy access for completing his work. The tool can be used without screw or hand adjustments of any kind.

BRIEF DESCRIPTION OF THE DRAWINGS

In the drawings:

FIG. 1 is a perspective view of my tool;

FIG. 2 is a top plan thereof;

FIG. 3 is a side elevation thereof; and

FIG. 4 is an end elevation thereof.

DETAILED DESCRIPTION OF PREFERRED EMBODIMENTS

Referring now to FIGS. 1-4, an elongated handle 10 typically 20 inches long and one-half inch in diameter extends horizontally. One end has a flat surface 12 extending at an angle of 45° with respect to the axis of the

handle.

A flat vertical plate 14 typically 1½ inches wide, 2 inches long and ⅛ of an inch thick is disposed at the one end with surface 12 being secured to one surface of the plate along the longitudinal center line at a point adjacent the top horizontal edges of the plate. The handle thus intersects the plate at a 45° angle.

The tool can then be used as previously described.

While I have described my invention with particular reference to the drawings, such is not to be considered as limiting its actual scope.

I claim:

1. A tool for rebuilding a disc brake comprising: an elongated horizontal handle; and a vertical plate adapted to be inserted in an opening between pads of said disc brake and secured to one end of the handle, the handle being joined to the plate at an acute angle.
2. The tool of claim 1 wherein the plate is a rectangle 20 with a vertical longitudinal direction, the handle being secured to one surface of the plate at a point adjacent the top end along the longitudinal center line.
3. The tool of claim 2 wherein the acute angle is about 45°.
4. The tool of claim 3 wherein the handle is of circular cross section.
5. The tool of claim 4 wherein the handle is about 20 inches long and about one-half inch in diameter, and the plate is about 1½ inches wide about 2 inches long and about ⅛ inches thick.
